T. I. GILBERT,
TRUNK APPLIANCE,
APPLICATION FILED MAY 9, 1921.

1,415,169.

Patented May 9, 1922.

UNITED STATES PATENT OFFICE.

TILMON I. GILBERT, OF LOS ANGELES, CALIFORNIA.

TRUNK APPLIANCE.

1,415,169.

Specification of Letters Patent.

Patented May 9, 1922.

Application filed May 9, 1921. Serial No. 468,073.

To all whom it may concern:

Be it known that I, TILMON I. GILBERT, a citizen of the United States, residing at Los Angeles, in the county of Los Angeles, State 5 of California, have invented new and useful Improvements in Trunk Appliances, of which the following is a specification.

My invention relates to trunk appliances, and particularly pertains to a follower for 10 holding the clothing compactly in a wardrobe trunk when packed and in transit, said follower being so shaped as to form an ironing board which may be supported by said trunk when opened, and readily and conveniently adjusted into a position of utility 15 for ironing purposes.

Other objects of my invention will appear in the following description, will be pointed out in the claims, and illustrated in the 20 accompanying drawings, in which:

Fig. 1 is a perspective view of an opened wardrobe trunk showing my invention applied thereto in a position of utility as an ironing board.

Fig. 2 is an enlarged vertical sectional view through the wardrobe section of the trunk, showing in full lines my invention adjusted in position when in use as an ironing board, and in dotted lines in the position 30 it would assume when folded away in the trunk when utilized as a clothing follower.

Fig. 3 is a plan section taken on the line 3—3 of Fig. 2.

In carrying out my invention 5 represents the drawer section of a wardrobe trunk of usual construction, and 6 the wardrobe section of the same, which are hinged together in the usual manner. The section 6 is provided with the usual hinged end cover 7, and 40 the hanger bars 8 upon which the hangers 9 may be supported.

Secured to the oppositely disposed sides 10 and 11 of the wardrobe section 6 and disposed just below the hanger bars 8 are rack bars 12, the teeth of which are preferably 45 of hooked formation, said hooks projecting backwardly as clearly shown in the drawings. The combined follower and ironing board 13, comprises a flat member 14, which 50 may be suitably padded, and having a rod 15 passing transversely through its broad end and secured thereto against lateral movement in any desired manner. The ends 55 of rod 15 extend beyond the edges of the member 14 and are adapted to rest in the notches 16 formed between the teeth of bars

12 and are provided with suitable buttons 17 which engage with the sides of bars 12 to prevent lateral movement of the member 14. Hinged at 18 to the narrow end of 60 member 14 is a leg member 19 adapted to rest upon the floor and support the free end of said member when adjusted to be utilized as an ironing board.

By the foregoing recited construction it 65 will be obvious that the member 14 may be conveniently and adjustably supported by the trunk member 6 on one of its ends and by the folding leg 19 on its opposite end when utilized as an ironing board, and when ad- 70 justed in the outer notches 16 in this position, the entire ironing surface may be conveniently used.

When the trunk is packed for storage or transportation, the clothing is placed in the 75 usual manner on the hangers 9, the leg 19 is folded upwardly against the member 14, and tied thereto by means of a tape 20, and then the rod 15 is adjusted in the proper notches 16 to hold the clothing compactly pressed 80 against the rear wall 21 of trunk member 6, as clearly shown in dotted lines in Figs. 2 and 3 of the drawings.

In order that the lower end of the member 14 may be held steadily and rigidly 85 against swinging on the pivot rod 15, I provide a spring strap member 22 which is secured at 23 to the floor wall 24 of the trunk, said spring member being serrated, and the lower end of the member 14 is adapted to 90 engage in said serrations, when adjusted against the clothing.

It will be obvious that the member 14 may be readily removed from the trunk and utilized for any desired purpose independently 95 thereof, or that when used as a follower it may be reversed from the position shown in dotted lines, in order that a smooth surface will contact with the clothing, instead of the leg 19.

What I claim is:

1. In a wardrobe trunk having a garment hanging compartment, a pair of oppositely disposed toothed rack bars secured in said compartment adjacent one end thereof, a 105 combined garment follower and ironing board provided at one of its ends with a cross bar, the ends of said bar adapted to pivotally and detachably engage with the teeth of the rack bars, and a supporting leg hingedly 110 secured to the free end of the combined follower and ironing board.

2. In a wardrobe trunk having a garment hanging compartment, a pair of oppositely disposed toothed rack bars secured in said compartment adjacent one end thereof, a 5 combined garment follower and ironing board provided at one of its ends with a cross bar, the end of said bar adapted to detachably and pivotally engage the toothed rack bars, a supporting leg hingedly secured 10 to the free end of the combined follower and

ironing board, and means mounted in said trunk compartment for detachably engaging the free end of the combined follower and ironing board to hold the same in an adjusted position when used as a garment fol- 15 lower.

In witness that I claim the foregoing I have hereunto subscribed my name this 13th day of April, 1921.

TILMON I. GILBERT.
